CAR ROOF

Paul E. Finger, New Kensington, Pa., assignor to
 Standard Railway Equipment Manufacturing
 Company, New Kensington, Pa., a corporation
 of Delaware

Application February 27, 1939, Serial No. 258,722

12 Claims. (Cl. 108—5.4)

This invention relates to car roofs, and more particularly to metal car roofs of the type wherein the roof sheets form a roof having alternating upper and lower panels and are connected by rigid upstanding seams in the lower panels, and the running board is supported by the seams and upper panels. The principal objects of the present invention are to devise a construction which will better provide for the support of the running board, which will be self-cleaning for cinders and moisture, which will provide hand holds for the trainmen above the upper panels and which will be strong, durable, simple and economical. The invention consists in the parts and in the arrangements and combinations of parts herein-after described and claimed.

In the accompanying drawings, which form part of this specification and wherein like symbols refer to like parts wherever they occur,

Fig. 1 is a plan view of a portion of a car roof construction embodying my invention,

Fig. 2 is an enlarged vertical transverse section through the ridge portion of the roof on the line 2—2 in Fig. 1,

Fig. 3 is a vertical transverse section on the line 3—3 in Fig. 1,

Fig. 4 is an enlarged vertical longitudinal section on the line 4—4 in Fig. 1,

Fig. 5 is a vertical longitudinal section at the ridge on the line 5—5 in Fig. 1,

Fig. 6 is an enlarged fragmentary vertical longitudinal section on the line 6—6 in Fig. 1,

Fig. 7 is a vertical transverse section on the line 7—7 in Fig. 1,

Fig. 8 is a section similar to Fig. 2, showing a modification of the invention,

Fig. 9 is a view similar to Fig. 3, showing another modification,

Figs. 10 and 11 are vertical longitudinal sections on the line 10—10 and 11—11, respectively, in Fig. 9; and

Fig. 12 is a section similar to Fig. 4, showing another modification.

In the accompanying drawings, my invention is shown in connection with a car roof having alternating upper and lower panels A and B, which slope downwardly from ridge to eaves of the car, and rigid upstanding seams C in the upper panels intermediate between the sides thereof. Said roof is made up of metal roof sheets 1 that span the car from side plate 2 to side plate 2 of the car and have their ends bent down and secured by rivets 3 to the respective side plates. The roof sheets 1 are provided along their adjacent margins with upstanding flanges

4 that are straddled by seam caps 5, all secured together by rivets 6, the ends of said caps being bent down over the side plates and secured thereto by the securing rivets 3 for the down-turned ends of the roof sheets. Preferably the middle portions of the sheets are raised to form the upper panels A, which decrease in depth from the ridge towards the eaves of the car and merge into the plane of the lower panels B adjacent to the side plates 2, and the side marginal portions of adjacent sheets are connected by the seams C to form the lower panels B.

The roof is provided with a metal longitudinal running board D comprising sections disposed in endwise alignment along the ridge of the roof with their upper surfaces disposed substantially at the level of the ridge portions of the roof seams C. The adjacent ends of the running board sections D are secured to the roof seams C by metal angle brackets 7 that are disposed on opposite sides of said seams with one flange down and secured flatwise to the sides of the seam caps 5 by the securing rivets 6 therefor and with the other flange extending outwardly beneath the end of an adjacent running board section and secured thereto at the corners thereof by vertical rivets 8 having flat upper heads. The portions of the roof seams located between the spaced ends of the running board sections are protected by means of sheet metal flashings 9 having hollow upstanding ribs that straddle said seams and outstanding base flanges 10 interposed between the outstanding top flanges of the running board bracket 7 and the overlying end portions of said sections.

As shown in Figs. 1 to 7, inclusive, each of the metal running board sections D has depending side marginal flanges 11 and relatively wide longitudinal tread portions 12 separated by relatively narrow channels 13 formed by a series of spaced longitudinal hollow ribs 14 on the under side of said section between said side marginal flanges. The tread portions 12 are provided with series of bossed-openings 15 that are spaced apart longitudinally of said portions from end to end thereof; and the bottoms of the channels 13 are provided with series of longitudinally spaced drain openings 16. As shown in Fig. 7, the top lateral flanges of the running board brackets 7 extend between the depending side marginal flanges of adjacent running board sections D and are offset downwardly, as at 7a, intermediate between their ends to form depressed seats for the ends of the depending ribs 14 of said sections. The base flanges 10 of the flashings 9

are likewise depressed, as at 10a, intermediate between their ends to seat within the depressed portions 7a of the outstanding top flanges of said running board brackets.

- 5 In the construction shown in Figs. 1 to 7, inclusive, the upper panels A of the roof are provided along their longitudinal side edges with raised ribs 17 whose ridge portions have substantially flat and horizontal tops 18 that form seats 10 for the depending ribs 14 of the running board sections located thereabove; and from these flat ridge portions, the ribs incline downwardly, as at 19, at a relatively steep angle and merge into the plane of the upper panels adjacent to and on 15 opposite sides of the running board sections. As shown in Fig. 12, the upper roof panel may be provided along its middle with a third running board supporting rib similar to the side marginal ribs 17 of said panel.
- 20 As shown in Figs. 2 and 3, the depending side marginal flanges 11 of the running board sections are provided with lateral foot flanges 20 that are turned inwardly at an angle corresponding to the slope of the end portions 19 of the running 25 board supporting ribs of the upper roof panels and rest flatwise upon said ribs. In the modification shown in Fig. 8, the foot flange 20a of the depending side marginal flange of the running board sections is disposed horizontally; and the 30 downwardly sloping end portion of the running board supporting rib of the upper roof panel is provided with a horizontal step 20b adapted to support said horizontal foot flange.

In the modification shown in Figs. 9 to 11, inclusive, the upper roof panel has its running board supporting ribs 17a located inwardly of its edges of said panels and have their end portions 19a inclined downwardly at a relatively small angle so as to merge into the plane of the upper 35 panels adjacent to the ends thereof; and the depending side marginal flanges 11a of the running board section are shown without base flanges and with their lower edges spaced above said ribs.

By the arrangement described, the ribs formed 40 in the upper panels of the roof serve to increase the strength and rigidity of said panels and form horizontal seats for supporting the running board intermediate between the roof seams. The depending flat-bottomed reinforcing and stiffening 45 ribs of the running board sections are all of the same depth and are all supported flatwise on the flat horizontal portions of the ribs of the upper roof panels; and the additional support afforded by said ribs between seams makes it possible to 50 make the running board sections of comparatively light gage metal and to decrease the depth of said ribs of said sections. The construction prevents the accumulation of cinders and moisture between the running board and the greater 55 portions of the upper panels of the roof and also provides hand holds for the trainman along the edges of the running board above the upper roof panels.

What I claim is:

- 60 1. A car roof comprising metal sheets formed into a longitudinal series of alternating upper and lower panels and a running board extending longitudinally of said roof at the ridge, the ridge portions of one of said series of upper and lower 65 panels having raised ribs therein that form seats for said running board.

2. A car roof comprising metal sheets formed into a longitudinal series of alternating upper and lower panels and a running board extending longitudinally of said roof at the ridge, said upper 70

panels having raised stiffening ribs formed therein that are disposed longitudinally thereof and have flat and horizontal tops that constitute supports for said running board.

3. A car roof comprising metal roof sheets 5 formed into a longitudinal series of alternating upper and lower panels and a running board extending longitudinally of said roof at the ridge, said upper panels having raised longitudinal ribs formed therein with substantially flat and horizontal ridge portions that constitute seats for said running board, said ribs inclining downwardly on opposite sides of said running board and merging into the plane of said upper panels.

4. A car roof comprising metal sheets formed 15 into a longitudinal series of alternating upper and lower panels and a running board extending longitudinally of said roof at the ridge, the ridge portions of the upper panels having raised longitudinal ribs formed therein with horizontally disposed flat-topped ridge portions that constitute seats for said running board, said ribs decreasing in height on opposite sides of said running board and merging into the plane of said upper panels adjacent to the eaves ends thereof.

5. A car roof comprising metal sheets formed into a longitudinal series of alternating upper and lower panels and connected by upstanding seams located in said lower panels, and a running board extending longitudinally of said roof 30 at the ridge and sustained by said seams, the ridge portions of said upper panels having raised ribs therein that form supports for said running board between said seams.

6. A car roof comprising metal sheets formed 35 into a longitudinal series of alternating upper and lower panels and a metal running board extending longitudinally of said roof at the ridge, the ridge portions of said upper panels having raised longitudinal ribs formed therein with flat-topped horizontal ridge portions, said running board having spaced longitudinal ribs on the underside thereof that seat upon the flat-topped horizontal ridge portions of the ribs of said upper panels.

7. A car roof comprising metal sheets formed into a longitudinal series of alternating upper and lower panels and a metal running board extending longitudinally of said roof at the ridge, said upper panels having raised longitudinal ribs 50 formed therein with horizontal flat-topped ridge portions that support said running board and end portions inclining downwardly on opposite sides of said ridge portions, said running board having depending side marginal flanges that terminate in laterally bent foot flanges that bear flatwise upon the downwardly inclined end portions of said ribs.

8. A car roof comprising metal sheets formed into a longitudinal series of alternating upper and lower panels and a metal running board 60 extending longitudinally of said roof at the ridge, said upper panels having raised longitudinal ribs formed therein with flat and horizontal ridge portions and downwardly inclined end portions, 65 said running board having depending ribs on its underside that seat upon the flat horizontal ridge portions of said ribs of said upper panels and depending side marginal flanges that terminate in laterally bent foot flanges that bear flatwise 70 upon the downwardly inclined end portions of said ribs of said upper panels.

9. A car roof comprising metal sheets formed into a longitudinal series of alternating upper and lower panels and a metal running board 75

extending longitudinally of said roof at the ridge, said upper panels having raised longitudinal ribs formed therein with flat-topped horizontal ridge portions that support said running board and end portions that incline downwardly from said ridge portions on opposite sides of said running board, said running board being provided with depending side marginal flanges that terminate in horizontally disposed foot flanges and the inclined end portions of said ribs having horizontal steps formed therein adapted to form seats for said horizontal foot flanges.

10. A metal car roof sheet adapted to span from side to side of a car and having a raised panel extending substantially from end to end, said panel having a raised rib therein extending longitudinally across the longitudinal middle of said panel, and the top face of the middle portion of said rib being flat and wide enough to 15 constitute a seat for a running board.

11. A metal car roof sheet adapted to span from side to side of a car and having a raised

panel extending substantially from end to end, said panel having a raised rib therein extending longitudinally across the longitudinal middle of said panel, and the top face of the middle portion of said rib being flat and wide enough to 5 constitute a seat for a running board, said rib having downwardly inclined end portions that merge into the plane of said raised panel.

12. A metal car roof sheet adapted to span from side to side of a car and having a raised 10 panel extending substantially from end to end, said panel having a raised rib therein extending longitudinally across the longitudinal middle of said panel, and the top face of the middle portion of said rib being flat and wide enough to 15 constitute a seat for a running board, said rib having downwardly inclined end portions that merge into the plane of said raised panel and are provided with flat and horizontal step portions.
